US00D824330S

(12) **United States Design Patent** (10) Patent No.: **US D824,330 S**
(45) Date of Patent: ** Jul. 31, 2018

(54) **WALL-MOUNTED ENERGY STORAGE SYSTEM**

(71) Applicants: **SUZHOU GCLSI SCIENCE AND TECHNOLOGY INDUSTRIAL APPLICATION RESEARCH INSTITUTE CO., LTD.**, Suzhou (CN); **GCL INTEGRATION TECHNOLOGY (SUZHOU) CO., LTD.**, Suzhou (CN); **GCL SYSTEM INTEGRATION TECHNOLOGY CO., LTD.**, Fengxian District (CN)

(72) Inventors: **Sancun Hao**, Suzhou (CN); **Renyi Fan**, Suzhou (CN)

(73) Assignees: **SUZHOU GCLSI SCIENCE AND TECHNOLOGY INDUSTRIAL APPLICATION RESEARCH INSTITUTE CO., LTD.**, Jiangsu (CN); **GCL INTEGRATION TECHNOLOGY (SUZHOU) CO., LTD.**, Jiangsu (CN); **GCL SYSTEM INTEGRATION TECHNOLOGY CO., LTD.**, Shanghai (CN)

(**) Term: **15 Years**

(21) Appl. No.: **29/575,742**

(22) Filed: **Aug. 29, 2016**

(30) **Foreign Application Priority Data**

Mar. 9, 2016 (CN) 2016 3 0065732

(51) LOC (11) Cl. **13-02**

(52) U.S. Cl.

USPC **D13/110**

(58) **Field of Classification Search**

USPC D13/107-110, 118-119, 144, 184; D14/155-242, 251, 432-434

(57) **CLAIM**

The ornamental design for a wall-mounted energy storage system, as shown and described.

DESCRIPTION

FIG. 1 is a perspective view of a wall-mounted energy storage system showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the figures are for the purpose of illustrating portions of the wall-mounted energy storage system that form no part of the claimed design.

1 Claim, 8 Drawing Sheets
